PUMP

Application filed October 19, 1931. Serial No. 569,561.

This invention relates to improvements in pumps of that type employed for elevating water from wells and especially wherein a gear pump is actuated by means of a motor.

One of the objects of the invention is to provide a pump adapted to be operated while submerged in a well tube so constructed as to be operated for a considerable period of time without necessitating frequent removal from the well tube for lubrication or repair. Other objects and advantages of the invention will appear hereinafter.

An illustrative embodiment of the invention is shown in the accompanying drawing, in which:—

Fig. 1 is an elevation of a structure in which the invention is embodied, portions thereof being broken away;

Fig. 2 is a plan view of the gear pump upon an enlarged scale; and Fig. 3 is a plan view of a centering device for the coupling shaft that connects the motor with the pump, the well tube being included and shown in section.

The illustrative embodiment of the invention consists essentially of a gear pump 1 having a discharge pipe 2 extending from its top and by which it is supported pendently in a well tube 3.

The pump 1 is of the gear type having gears 4 and 5 in a casing 6 provided with bores 7 and 8 respectively therefor and in which the said gears rotate oppositely. The gear 4 has trunnions 9 and 10 extending respectively from its ends entirely through the corresponding heads 11 and 12 for the casing 6, and the trunnion 10 has a polygonal extension 13. The gear 5 also has trunnions 14 that respectively extend entirely through the heads 11 and 12.

The head 12 on the lower end of the casing 6 has a suction chamber 15 that has communication with an inlet port 16, and also said casing has therein an outlet chamber 17 that has communication with the discharge pipe 2 through the head 11 in which said pipe has threaded connection.

The upper end of the discharge pipe 2 is suspended from a pedestal casting 18 that surmounts the top of the well tube 3 and has

communication with an outlet pipe 19 through a duct 20 made in said casting which also has connection therewith.

The lower end of the pedestal casting has an annular flange 21 that fits over the top of the well tube 3 and has a set-screw 22' therein for securing the pedestal casting in position thereon. The upper end of the pedestal casting constitutes the lower head of a motor 23 positioned thereon, the axis of said lower head being offset with respect to that of the well tube so that when the pump casing is positioned in the well tube in axial alinement therewith the armature shaft 24 of the motor is disposed in alinement with the trunnion 10 on the pump gear 4. The armature shaft 24 has operative relation with the pump gear 4 by means of a line-shaft 25, the upper end of which is connected with the armature shaft by a coupling 26 and at its lower end 70 with the extension 13 by a slip socket connection 27.

The pedestal casting 18 has a transverse partition 28 therein in which is supported a thrust bearing 29 through which the armature shaft 24 extends and by which downward movement of the armature shaft is prevented. The length of the line shaft 25 relative to the discharge pipe 2 upon which the pump is solely supported, and the longitudinal play of the extension 13 in the slip socket 27 on the drive-shaft, are such as to obviate vertical thrust of said line shaft and its slip coupling upon the trunnion 10 of the gear. Thus, it will be understood that the weight 85 of the line shaft 25 as well as the armature shaft connected therewith is entirely borne by the thrust bearing 29.

For the purpose of sustaining the discharge pipe 2 and the line shaft 25 respectively in proper eccentric alinement with respect to the axial center of the pump tube 3 there is provided one or more supports therefor, each constituting a disc 30 having secured thereon a clamp 31 in which is disposed a bushing 32 through which the line shaft extends and is revoluble therein, and which is firmly secured in place upon the discharge pipe 2 by means of a bolt 33. Such supports (one only being shown) are disposed in the well tube 100

at points suitably spaced apart to prevent buckling of the line shaft.

Preferably, the outlet pipe 19 has an extension connected therewith constituting a service pipe 34 provided with a valve 35, and also connected with said outlet pipe is provided a pressure controlled switch 36 of ordinary construction through which current is supplied to the motor through suitable conductors 37, whereby when the pressure developed in the outlet pipe through operation of the pump becomes excessive, the current supplied to the motor is automatically shut off.

A feature of the invention is in forming the pedestal casting so that when positioned upon the top of the well tube 3 the armature shaft 24, line shaft 25 and the trunnion 10 for the gear 4 are sustained in alinement with each other and the pump casing 1 while supported by the discharge pipe 2 is sustained in axial alinement with the pipe 2.

Another feature of the invention is the arrangement of ducts 38 and 39 made respectively in the heads 11 and 12 of the pump, that extend from the outlet chamber 17 inwardly to a point spaced from the axial center of the pump and through which escapes into the outlet chamber liquid entrapped between the teeth of the gears from the discharge sides thereof, thus relieving unnecessary pressure of liquid between the gears.

A further feature of the invention consists in so proportioning the trunnions 9 and 10 of the gear 4 and the trunnions 14 of the gear 5 relative to the openings in the heads through which they extend by making said trunnions of slightly smaller diameter than said openings whereby a sufficient quantity of liquid as it is forced through the pump escapes outwardly between the trunnions and the walls of the openings in which they revolve. Such passage of liquid is found to act as a lubricating means for the trunnions and obviates the necessity of a stuffing box for the trunnion 10 but is not sufficient in quantity to cause more than a negligible reduction of pressure within the pump while in operation.

If so desired a check valve 40 may be connected in the discharge pipe at a suitable point whereby back-flow of water through the pipe is obviated when the pump is idle.

In operation, the structure consisting bodily of the motor, pedestal casting, sup-

ports 30, pump, discharge pipe and the driving connection between the motor and the pump is placed upon the top of the well tube 3 with the bottom of the pedestal resting on the top thereof and secured in place by the set-screw 22', and with the pump submerged in the tube beneath the normal water level 41 therein. Current is then supplied through the conductors 37 and switch 36 to the motor, whereupon the pump is actuated by the motor causing flow of water through the discharge pipe 2, outlet pipe 19 and the service pipe 34. When the flow of water is checked or stopped, as by closing the valve 35 the increased pressure of water in the discharge line, due to continued action of the pump, causes the switch to open and thus shut off the current from the motor. When the valve is reopened and the pressure in the discharge line is relieved the switch automatically closes and operation of the apparatus is resumed.

I claim:—

1. A pumping mechanism consisting of a pedestal adapted to seat upon a well tube, a gear pump having a discharge pipe pendently connecting it with said pedestal, a motor mounted upon said pedestal the armature shaft of which is alined with one of the gears of said pump, a line shaft connecting said armature shaft with the said gear, and a supporting means secured to said discharge pipe and having a bearing through which said line shaft extends and rotates and adapted to fit within said well tube whereby said line shaft is sustained in proper alinement between the motor and said pump gear.

2. In pumping mechanism, a well tube, a pedestal on the top of said tube, a gear pump and complementary discharge pipe pendently disposed in said tube, driving means on the pedestal having an actuating connection with one of the gears of said pump, and trunnions on the gears of said pump that extend through corresponding openings in the pump housing, said openings and trunnions being so disposed as to permit continuous passage from said housing through said openings about the trunnions and into the well tube of a limited amount of liquid whereby said trunnions are lubricated.

In testimony whereof I affix my signature.

CLEMENT G. BRANSTRATOR.
